UNITED STATES PATENT OFFICE.

ALLEN E. SCOTT, OF SAN FRANCISCO, CALIFORNIA.

DRESS-FORM.

SPECIFICATION forming part of Letters Patent No. 727,464, dated May 5, 1903.

Application filed November 22, 1901. Serial No. 83,331. (No model.)

To all whom it may concern:

Be it known that I, ALLEN E. SCOTT, a citizen of the United States, and a resident of San Francisco, county of San Francisco, and State of California, have invented certain new and useful Improvements in Dress-Forms; and I do hereby declare the following to be a full, clear, and exact description of said invention, such as will enable others skilled in the art to which it most nearly appertains to make, use, and practice the same.

My invention relates to that class of wearing-apparel which are used by women as dress-forms; and it consists in providing the same with suitable means for creating a constant vacuum within while in operation, and further consists in the construction of its various parts.

The object of my invention is to produce a simple, convenient, hygienic device for drawing or concentrating the blood within the mammary glands for the purpose of developing its tissues.

Reference being had to the accompanying drawings, which form part of the following description, Figure 1 represents the bust of a woman wearing my invention. Fig. 2 is a similar view in different position. Fig. 3 is a top view of one of my improved dress-forms. Fig. 4 is a vertical section taken from dotted line 1 to 1 of Fig. 3, showing a part of a suction-pump secured thereon. Fig. 5 is an enlarged detail view of the valve, showing particularly the method of connecting same to the dress-forms. Fig. 6 is a similar view, but showing a modification of Fig. 5.

Similar letters of reference refer to similar parts throughout the drawings.

A represents my improved dress-form, which has a semiglobular or mammary-glands shape, curled outwardly and inwardly at the edge B, and a central aperture C. Around the central aperture just mentioned is a circular depression a, made deep enough to form a socket within the aperture, in which the check-valve D is permanently secured. This valve has its outer side preferably round and depressed to form the circular outwardly-projecting flange b, which rests upon the edge of the socket when in position, while the other end has the groove c to form a circular projecting outer edge, which may be forced out-

wardly against the inner side of the socket, thus adjusted constituting a simple air-tight joint. The inner arrangement of the valve 55 consists of chamber E, having its rear end round to form a suitable seat for the ball o', placed within, while its forward end has inward projections d to prevent the ball from dropping out. The ball just mentioned is 60 made less in diameter than the chamber and is adapted to close or open the aperture e, formed centrally through the rear end of the valve D, and to move freely when desired within the chamber between the seat previously mentioned and the projections.

The edge B may be covered with rubber g, as shown in Fig. 4, if desired, to smooth its bearing-surface and form a better joint.

In practice my invention is placed against 70 the breast inclosing the mammary glands to be developed and held in that position by means of straps adjusted, preferably, over the shoulders and around the body, as particularly shown in Figs. 1 and 2. I then connect 75 to the valve the suction-pump F, as illustrated in Fig. 4, by which I create a suction within, and thereby drawing or concentrating within the mammary glands the blood, thus forcing the development of its tissues. Following this operation the pump is removed 80 and may be replaced by the cap G, which is preferably made of flexible material, such as rubber, to prevent the air from getting in. Thus constructed and adjusted in the manner above described women could wear my invention as a dress-form while the object for which it is particularly intended is being carried out.

I have shown in Fig. 6 a modification of my 90 invention which relates to the adjustment of the valve and the pump, and consists in providing threads between the valve and the socket, so that the former could be screwed in place, and also to cut threads around the outer 95 side of the socket, so that the pump connections and the cap could be screwed in position.

I am aware that prior to my invention breast-pumps have been used for similar purposes; but none have been made to create a 100 constant suction with dress-forms, as is particularly the case in my invention, and, believing I have produced a convenient and useful article of manufacture.

What I claim, and desire to secure by United States Letters Patent, is—

1. A dress-form, comprising a semiglobular bottomless body having a central opening and 5 an annular groove surrounding the opening, and a check-valve mounted in said opening.

2. A dress-form, comprising a semiglobular bottomless body having a central opening, an outwardly-projecting wall surrounding the 10 opening and a depressed annular groove sur-

rounding the opening, and a check-valve held in said opening by the walls.

In testimony whereof I have affixed my signature, in presence of two witnesses, this 8th day of October, A. D. 1901.

ALLEN E. SCOTT.

In presence of—

W. M. PARK,
J. CORINSON.
